DECORATED METAL SHEET

Joseph J. Clement, Clarence, N.Y., assignor to Rigidized Metals Corporation, Buffalo, N.Y.

Filed Aug. 16, 1965, Ser. No. 86,599

Term of patent 14 years

(Cl. D54—2)

The single figure of the drawing is an elevational view looking directly at a face of a metal sheet showing my new design.

I claim:

The ornamental design for a decorated metal sheet, as shown.
